URINE SPECIMEN COLLECTION FUNNEL

Thomas N. Garland, Denver, Colo., assignor of thirty-seven and six-tenths percent to Carol Wendt; one percent each to Leon T. Howard, James R. Snedeker, Whitney B. Siebert, Robert F. Fiori, and Robert E. Wallace; five percent each to Darell W. Blair, and Norman D. Paschall; one percent to Pearl M. Blakeney; and nine percent to Edwin L. Spangler, Jr., and Max L. Wymore, doing business as Anderson, Spangler & Wymore, both of Denver, Colo.

Filed Jan. 19, 1968, Ser. No. 10,221

Term of patent 14 years

(Cl. D83—1)

FIG. 1.

FIG. 4.

FIG. 2.

FIG. 5.

FIG. 3.

FIGURE 1 is a top plan view of the urine specimen collection funnel, showing my new design;

FIGURE 2 is a front elevation thereof, the undisclosed rear side is a mirror image of the side shown;

FIGURE 3 is a bottom plan view;

FIGURE 4 is an end view in elevation; and,

FIGURE 5 is the opposite end view.

The broken line representing the collection bottle is shown for illustrative purposes only.

I claim:

The ornamental design for the urine specimen collection funnel, as shown and described.
